FRANK A. HOWARD AND NATHANIEL E. LOOMIS, OF ELIZABETH, NEW JERSEY, AS
SIGNORS TO STANDARD DEVELOPMENT COMPANY, A CORPORATION OF DELAWARE.

ART OF DISTILLING OILS.

Application filed April 10, 1922. Serial No. 551,354.

The present invention relates to the art of distilling oils, and more particularly to the continuous distillation of crude oils. It will be fully understood from the following description, illustrated by the accompanying drawings, in which:

Figure 1 illustrates diagrammatically an arrangement of apparatus for use in connection with the present invention, and

Fig. 2 illustrates diagrammatically a modified arrangement of apparatus, likewise suitable for use in the practice of the present invention.

Referring more particularly to Figure 1 of the drawings, the numerals 5, 5^a and 5^b indicate stills, for example horizontal cylindrical stills, of the usual type. These stills are provided respectively with vapor lines 6, 6^a and 6^b leading to vapor heat exchangers 7, 7^a and 7^b. From the vapor exchangers, vapor lines 8, 8^a and 8^b pass off through the condenser boxes 9, 9^a and 9^b to suitable receivers (not shown). The condensate lines 10, 10^a and 10^b likewise pass off from the respective exchangers, through the condenser boxes, in which the condensates are cooled. The stills 5, 5^a and 5^b are provided with valved inlet lines 11, 11^a and 11^b, and with valved outlet lines 12, 12^a and 12^b. Suitable steam lines 13, 13^a and 13^b may likewise be provided entering the stills.

The crude oil to be treated is forced by any suitable means, such as a pump (not shown) into the manifold 14, from which it passes into the vapor exchangers 7, 7^a and 7^b, as well as the exchangers 36, through the valved connections 15. In these exchangers, the oil is heated by the vapors issuing from the stills 5, 5^a and 5^b and from the vapor separators 34, and passes out through the valved connections 16, into the manifold 17. From the manifold 17 the preheated oil passes through line 18 into the line 11 leading to still 5; from this still residue is discharged through line 12 into the line 19 from which it enters still 5^a through line 11^a; from still 5^a residue passes through line 12^a into line 20, and from line 20 into still 5^b through line 11^b. The valved bypasses 21, 21^a and 21^b are provided so that any of stills 5, 5^a and 5^b can be by-passed if desired.

From the still 5^b residues pass through line 12^b into the line 22, which leads to any suitable pumping device, for example a

master pump 23, which forces it into a manifold 24. From the manifold 24 the residues are forced by feed pumps 25 which also serve as metering devices through lines 26 into heating coils 27, which form a part of a converting system. Any suitable or desirable number of such heating coils may be employed, two being illustrated in Fig. 1 of the accompanying drawing. The residues are forced by the feed pumps through the heating coils 27 in the manner described in our prior application Serial No. 471,737, filed May 23, 1921. In passing through the heating coils they are brought to a conversion temperature, the time of passage through the coils being such that only a small conversion of the oil into lighter products of the nature of gasoline takes place. The velocity of flow of the oil through the coils 27 is likewise so adjusted that no appreciable deposition of coke will take place therein. The conversion temperature to which the oil may be brought in passing through the coils 27, may be from 700 to 900° F., and is preferably in the order of 800 to 850° F. Steam, water, hydrocarbon gas, gasoline or any other suitable inert material, normally in the vapor or gaseous state at the temperatures prevailing in the heating coils 27, may be introduced by means of the valve connections 28, if necessary or desirable to increase the velocity of flow of the oil through the coils. From the coils the heated oil passes through lines 29 into the drums or enlarged chambers 30, of which

a plurality may be provided for each of the heating coils, in the manner described in our prior application above referred to. In the apparatus illustrated in the present drawings, two of the enlarged chambers or drums 30 are provided for each of the heating coils 27, connections being provided so that the oil may be passed into either of these drums, or into both simultaneously. In the drums 30 the heated oil is retained for a period sufficient to permit a substantial conversion into low boiling point products, for example, of the nature of gasoline. These drums may be thermally insulated by any suitable means, or may be mildly heated by some auxiliary heating device, preferably using waste heat or combustion gases, the external temperature used being, however, not sufficiently high to raise the walls of the drums to a temperature above, say 900° F. In the

- enlarged chambers 30 the oil is maintained at a conversion temperature, and leaves them at a temperature which is not higher than the outlet temperature from the coils 27, 6 and ordinarily 50 to 75° lower. All of the products of conversion pass out of the drums 30 together into the lines 31 provided with pressure release valves 32 and from these lines into the common line or manifold 33. 10 In passing through the pressure release valves 32, the pressure upon the products of conversion is very considerably lowered, say to a pressure of 10 to 50 pounds gauge. From the line 33 the products of conversion 15 enter the vapor separators 34 through valved lines 35. Any number of the vapor separators 34 may be employed, two being shown in the accompanying drawing. In the vapor separators, a separation of the 20 products into vapors and liquids or residues takes place. The vapors pass off through lines 35^a into the exchangers 36, and from the latter vapor lines 38 pass off through suitable condenser coils (not shown) in the 25 condenser boxes 39 and condensate lines 40 pass off through suitable cooling means in the condenser boxes, or the condensate, without cooling, may be returned to the vapor separator through reflux lines 40^a. 30 From the vapor separators the liquid residues pass through valved connections 41 into manifold 42. At one end the manifold 42 is provided with a pressure release valve 43, through which it communicates by valved 35 line 44 with the line 18 through which the preheated crude oil passes to the still 5. At its other end the manifold 42 communicates, through a valve 45, with a suitable cooler 46, which discharges through line 47 to any 40 suitable receiving tank, a pump being interposed if desired (not shown). 45 An auxiliary line 48 communicates with the crude line 18 before the point of connection of the line 44 and is provided with a suitable valve 49. A pump 50 connected with this line is adapted to force oil into the line 51 communicating with the manifold 33. 50 In beginning operation with a suitable crude oil, for example, Burk Burnett crude, the oil is forced by any suitable pump through the manifold 14, the heat exchangers, the manifold 17 and the line 18 into the crude stills 5, 5^a and 5^b, which are operated as ordinary continuous crude stills 55 to take off as distillates up to about 50% of the crude oil, steam being introduced, if desired, through the lines 13, 13^a and 13^b in the ordinary way. The oil passes successively through the stills, the by-pass valves 21, 21^a and 21^b being closed. The residue from the last still 5^b passes out through connection 12^b and line 22 to the master pump 23, the residue being at a temperature of 500 to 600° F. The master pump 23 forces the oil 60 into the manifold 24, and from this it is

picked up by the feed pumps 25, which force the oil through the heating coils 27 and the enlarged converting drums 30. By means of the master pump 23 and the feed pumps 25, the oil is maintained under a pressure in the heating coils 27 and the enlarged chambers 30 such that the oil is retained in the liquid state until a substantial conversion thereof has taken place. Thus, it may suitably be maintained at a pressure 75 of 100 to 500 pounds per square inch in the heating coils 27 and the enlarged chambers 30. A suitable conversion temperature of say 750 to 900° F. is attained at the outlets of the heating coils 27, and is substantially 80 maintained in the enlarged chambers 30. In the lay-out illustrated in Fig. 1, in which two of the enlarged chambers 30 are connected with each of the heating coils 27, the chambers 30 are preferably used alternately, one being cleaned while the other is in use. From the enlarged chambers 30 the conversion products pass through line 31 and pressure release valves into line 33, which leads to the vapor separators 34. In passing through 85 the pressure release valve 32, the pressure on the conversion products is reduced to 25 to 50 pounds per square inch. In the vapor separators 34, a separation of vapor and liquid products of conversion takes place, the vapor products, consisting largely of gasoline and kerosene-like fractions, passing off through vapor lines 35^a to the heat exchangers 36. The heavier products condensed in the heat exchangers 36 pass 90 through lines 40 to suitable receivers or optionally, are refluxed to the vapor separator through 40^a, and the uncondensed products pass through lines 38 to suitable condensers 95 and receivers. 100

The liquid residues separated in the vapor separators 34 pass out through lines 41 to the manifold 42, which is connected through pressure release valve 43, to the line 18 by which the preheated crude oil from the heat exchangers enters the first crude still 5. The addition of the tars from the separators to the incoming crude oil further preheats the latter. The tars from the vapor separators pass on through the crude stills with the crude oil and are subjected to the same distilling conditions in passing therethrough. The proportion of tars or residues from the vapor separators entering the crude line 18 may be varied, any suitable proportion thereof being diverted from the line 42 into the tar cooler 46 by opening the valve 45 to any desired degree. If it is desired to cool the products of conversion entering the vapor separators 34, this may be done by opening valve 49 and forcing crude oil from the line 18 to line 48 and line 51 by means of pump 50 into the line 33, in which they mingle with the products of conversion coming from the enlarged chambers 105 110 115 120 125 130

30 and pass into the vapor separators. Of course, this would not be done if valve 45 were open.

Although both of the vapor separators 34 5 may be used at the same time, they may likewise be used alternately, if desired, one being employed while the other is being cleaned, and vice versa.

In Fig. 2 a modified arrangement of apparatus is illustrated, in which the invention 10 may be carried to effect. In this embodiment of the invention, the vapor separators for the products of conversion from the converting coils and enlarged chambers are 15 dispensed with, the products of conversion being introduced directly into the crude stills.

In Fig. 2, the numerals, 60, 60^a, 60^b, 60^c and 60^d indicate stills, arranged in series. Each 20 of the stills is provided with vapor lines 61 leading to a heat exchanger 62, in which a part of the heat of the vapors is employed to preheat the incoming crude oil. Condensates from the vapor heat exchangers 62 are 25 discharged through condenser lines 63 and vapors from the exchangers are discharged through the cooler lines 64 to suitable receiving tanks (not shown). The numerals 65 indicate condenser boxes through which the 30 lines 63 and 64 pass.

Crude oil enters the system through the manifold line 66, from which it passes through valved connections 67 into the vapor heat exchangers 62. From the ex- 35 changers it passes through valved lines 68 into the manifold 69. The preheated oil from the manifold 69 passes through line 70 and the valved connection 72 into still 60. From still 60 residues pass through outlet 40 line 73 into the line 74 and from the line 74 through the valved connections 72^a into still 60^a. In a similar way the residues from still 60^a pass into still 60^b and so on through the series of stills, corresponding inlet and discharge lines being indicated by the same 45 numerals with suffixes corresponding to those of the stills. From the still 60^d, the residues pass through lines 73^d into the line 75 leading to the master pump 76. Valved by-pass 50 connections 77 are provided so that any one of the stills may be by-passed or the flow therethrough controlled. Each of the stills is likewise provided with a suitable steam connection 78.

55 The residues from still 60^d, after leaving the master pump 76, pass into the manifold 78, from which they are drawn by feed pumps 79 into the lines 80 leading to the heating coils 81 of the conversion system. In 60 the heating coils they are brought to a conversion temperature, as described in connection with the preceding embodiment of this invention, and immediately pass through lines 82 into the enlarged chambers 83, of 65 which any number, for example two, may

be provided for each heating coil. The operation of the heating coils 81 and the enlarged chambers 83 in effecting conversion of the residues is the same as described in the preceding example, the enlarged chambers being employed simultaneously or alternately, as desired. From the enlarged chambers 83 the products pass through lines 84, in which pressure release valves 85 are provided, to a common line or manifold 86. 70 As in the preceding example, the oil, in passing through the heating coils 81 and drums 83, is maintained under a pressure sufficient to keep it in the liquid state until substantial conversion has been effected. The products 75 of conversion, under the reduced pressure of, say, about 25 pounds per square inch prevailing in the manifold 86, may be passed through valved lines 87 into the stills 60, 60^a, 60^b, 60^c and 60^d. Ordinarily, a part of 80 the products of conversion are permitted to pass into each of the stills, although, if desired, one or more of the stills may be kept free from such products.

The manifold 86 likewise connects with a 90 line 88 leading to a cooling device 89, a valve 90 being provided to control the rate of flow.

In the operation of the apparatus illustrated in Fig. 2, the crude oil flows in succession through the stills 60, 60^a, 60^b, 60^c and 60^d. The products of conversion in the manifold 86, which are at a high temperature, are introduced in suitably proportioned amounts into the stills through the valved 95 lines 87. The stills into which they are introduced consequently act also as separators for the vapor and liquid products of conversion, the latter following the course of travel of the crude oil through the series of 100 stills. A part of the products of conversion may be passed from the line 86 to the cooling device 89, if, in any case, the total quantity of products of conversion become too 105 large for the capacity of the stills. It is sometimes desirable to introduce the products of conversion from the line 86 only into a certain number of the stills, for example, 60, 60^a and 60^b, instead of into all of the 110 stills.

Although the present invention has been described in connection with specific forms of apparatus in which it may be practiced, it is not intended that the details of these embodiments shall be regarded as limitations upon the scope of the invention, except in so far as included in the accompanying 115 claims.

We claim:

1. The method of distilling and converting hydrocarbon oils which comprises passing the oil through a heated chamber in which its lighter constituents are removed, passing the residues continuously through a heat conversion system wherein it is main- 125

tained at a conversion temperature under a pressure sufficient to maintain it substantially entirely in the liquid phase until considerable conversion has taken place, reducing 5 the pressure upon the products of conversion of said residues, separating said products into liquid and vapor constituents, and commingling at least part of the liquid constituents with fresh oil being subjected to 10 fractional distillation.

2. The method of distilling and converting hydrocarbon oils which comprises continuously performing the following steps in succession: passing the oil through a heated 15 zone not substantially above atmospheric pressure, removing vaporized constituents therefrom during said passage, heating the residues to a conversion temperature while under pressure, reducing the pressure on the 20 products of conversion, separating vapor from liquid products and commingling separated liquid products of conversion with fresh oil entering the process.

3. The method of distilling and converting 25 hydrocarbon oils which comprises passing the oil successively through a series of stills wherein the lower boiling portions thereof are removed, passing the residues continuously through a converting system 30 wherein they are subjected to a conversion temperature while being maintained at a pressure such that the oil is maintained substantially in the liquid state until a considerable conversion thereof has taken 35 place, withdrawing the products of conversion from said converting system and introducing at least a part of said products of conversion into the stills wherein the initial distillation of the oil takes place.

40 4. The method of distilling and converting oils which comprises passing crude oil successively through a series of stills to remove the lower boiling fractions thereof, passing the residues from said oil continuously through a conversion system wherein 45 they are subjected to a conversion temperature until a substantial conversion has taken place, maintaining a pressure upon the conversion system such that the oil is maintained in the liquid state until a considerable conversion thereof has taken place, withdrawing the products of conversion from the converting system and reducing the pressure thereupon, separating the liquid and vapor products of conversion and admixing at least part of the liquid products of conversion with the crude oil entering the series of stills.

5. The method of distilling and converting 60 hydrocarbon oils which comprises passing crude oil successively through a series of stills whereby the lower boiling point portions thereof are removed, forcing the residues continuously through a conversion system wherein they are brought to a con-

version temperature and maintained at such temperature until substantial conversion has taken place, maintaining pressure upon the oil in the conversion system sufficient to keep the oil in the liquid state until substantial conversion thereof has taken place, simultaneously withdrawing the products of conversion from the conversion system through a common line and reducing the pressure thereupon, and distributing at 75 least a part of the products of conversion among stills of the series of stills wherein the distillation of the crude oil takes place, whereby a separation of the vapor and liquid products of conversion takes place therein simultaneously with the distillation of the crude oil.

6. In apparatus for the distillation and conversion of oils, a series of stills, means for passing oil successively through said stills, a converting system, means for forcing residues from the last of said stills to said converting system under pressure, means for withdrawing products of conversion from said converting system and for releasing the pressure thereupon, a common line into which the products of conversion are received, separating chambers into which said common line leads and wherein a separation of liquid and vapor products of conversion takes place, and means for introducing the liquid products of conversion into the series of stills.

7. In apparatus for the distillation and conversion of oils, a still, means for introducing oil into said still, a heated converting system, means for forcing residues from the still to said converting system under pressure, means for withdrawing products of conversion from said converting system and for relieving the pressure thereupon, a separation chamber into which said products of conversion are introduced and wherein a separation of liquid and vapor products of conversion takes place, and means for introducing the liquid products of conversion into the still.

8. In apparatus for the distillation and conversion of oils, a series of stills, means for passing oil successively through said stills, a heated converting system, means for forcing residues from the last of said stills to said converting system under pressure, means for withdrawing products of conversion from said converting system and for relieving the pressure thereupon, a common line into which the products of conversion are received, and means for introducing products of conversion from said line into the several stills.

9. In apparatus for the distillation and conversion of oils, a still, means for introducing oil into said still, a heated converting system, means for forcing residues from said still to said converting system under

pressure, means for withdrawing products of conversion from said converting system and for relieving the pressure thereupon, a separating chamber into which said products are introduced and wherein a separation of liquid and vapor products of conversion takes place, means for commingling the liquid products from said separating chamber with the oil entering the still, and 10 means for diverting at least a portion of said liquid products to a cooling device.

10. In apparatus for the distillation and conversion of oils, a series of stills, means for passing oil successively through said 15 stills, a heated converting system, means for forcing residues from the last of said stills to said converting system under pressure, means for withdrawing products of conversion from said converting system and 20 for relieving the pressure thereupon, a common line into which the products of conversion **are** received, a valved connection between **said** line and each of said stills,

a cooling device, and a valved connection between said line and said cooling device, 25 whereby at least a part of the products of conversion in said common line may be diverted into said cooling device.

11. In apparatus for the distillation and conversion of oils, a still, means for introducing oil into said still, a heated converting system, means for forcing residues from said still to said converting system under pressure, means for withdrawing products of conversion from said converting system 35 and for relieving the pressure thereupon, a common line into which the products of conversion are received, a valved connection between said line and the still, a cooling device, and a valved connection between 40 the line and the cooling device whereby at least a part of the products of conversion may be diverted to said cooling device.
